M. T. DONOHO.
NAP RESTORING AND SHINE REMOVING MACHINE.
APPLICATION FILED NOV. 10, 1921.

1,432,976.

Patented Oct. 24, 1922.

UNITED STATES PATENT OFFICE.

MURRAY T. DONOHO, OF WASHINGTON, DISTRICT OF COLUMBIA.

NAP-RESTORING AND SHINE-REMOVING MACHINE.

Application filed November 10, 1921. Serial No. 514,356.

To all whom it may concern:

Be it known that I, MURRAY T. DONOHO, a citizen of the United States, and resident of Washington, in the District of Columbia, have invented certain new and useful Improvements in Nap-Restoring and Shine-Removing Machines, of which the following is a full, clear, and exact description.

My invention relates to a hand operated, power driven nap restoring and shine removing machine, which is at all times under perfect control of the operator.

One of the objects of my invention is to provide a machine of this character having one or more series of rigid penetrating pins, which are rapidly reciprocated, whereby the pins enter the fabric being treated and open it up, with the result that the shine is easily and rapidly removed, and the worn garment or fabric is greatly refreshed and is given an appearance closely approximating that of new material.

Another purpose of the invention is to secure these highly desirable results without any scratching abrasive or other destructive action on the fabric being treated.

Still another object of my invention is to facilitate the cleansing of garments or other fabric.

It is well known, of course, that when the nap of a garment has been worn off, or has become "feltd" from pressure or other causes, the appearance of the garment is spoiled by becoming shiny, and the previous means which have been devised to improve the appearance of the fabric have either had a destructive action on the fibre, or they produced only very temporary results, the shiny appearance returning after the garment has had but little wear. In the apparatus which I have devised there are a number of rigid entering pins, the size and spacing of which will be dependent upon the character of the goods being treated, and these pins

are reciprocated rapidly, so that as the apparatus is drawn over the garment the pins enter the material and open up the fibre thereof, and because of the rapidity of reciprocation each minute area is entered many times, and thus is accomplished, not what might be termed an artificial removal of the shine, but an actual opening up or fluffing of the fibre, so that the fabric is actually resorted to a condition which is sub-

stantially the same as it was originally. 55 And it is thus obvious that the shine will not return with short use.

I will now proceed to describe one particular form of my invention, it being understood that those skilled in the art may 60 make many changes and modifications therein, without departing from the spirit of the invention as defined in the appended claims; and the drawings forming part of this specification are therefore to be considered merely as illustrative, and not in any limiting sense.

Like numerals refer to like parts throughout the several views of the drawings.

In the drawings: 70

Figure 1 is a perspective view of the complete apparatus, shown as in actual use.

Figure 2 is a bottom plan view of the apparatus, the motor being omitted.

Figure 3 is an enlarged detail view, 75 partly in section, showing the connection between the motor shaft and the connecting rod, and other details of construction.

Figure 4 is a sectional view taken on the line 4—4 of Figure 3, looking in the direction of the arrows. 80

Figure 5 is an enlarged detail sectional view, showing the connection between the connecting rod and the reciprocable plate.

Figure 6 is an enlarged transverse vertical sectional view taken through the frame, and showing the means for mounting the reciprocable plate in the frame; and, 85

Figure 7 is an enlarged fragmentary perspective view of a slightly modified form of 90 the invention.

Referring to the drawings more in detail, numeral 1 indicates the frame of the apparatus, which may be of any desired shape, and which may be attached to any desired 95 type of motor 2, by means of screws 3. It is not essential that the motor be carried by the frame, as obviously the motor could be operatively connected to the reciprocable plate by flexible shafting.

A connecting rod 4 passes through an opening 5 in the frame and is connected to a crank pin carried by the motor shaft 7.

A plate 8 is mounted for reciprocation in the frame in any desired manner, as by 105 means of guides 9. For the purpose of connecting the connecting rod to the reciprocable plate in such manner that the parts

may be readily disconnected and the plate removed, I provide the plate with a boss 10 which is adapted to receive a screw 11 which passes through an eye in the connecting rod, 5 and thus serves the function of a connecting pin. It will be understood, of course, that the particular means for connecting the various parts of the apparatus form no essential part of the invention, and I reserve 10 the right to use such details of construction as may be found most desirable.

Rigid entering pins 12, preferably metallic, are mounted in the reciprocable plate 8, and it may be noted here that this plate may 15 consist of a single piece of metal as shown in Figures 5 and 6, or it may be composed of a plurality of sheets with the pins secured between them, as shown in Figure 7.

For purposes which will appear herein- 20 after, it is found desirable not to make the pins of the same length, but to gradually increase the length thereof toward the center, so that the line of points follows the arc of a circle.

25 To reduce the friction between the bottom surface of the reciprocable plate and the fabric being treated, I find it desirable in the construction of the plates to have a large portion thereof pressed upwardly, so that a 30 recess 13 is formed in the bottom of the plates, while the tops thereof are arched as indicated by numeral 14. As clearly shown in Figure 2, a margin is left between the recessed portion and the side edges and end 35 of the plate to which the pins are attached.

To permit the removal of the plate from the frame, the front of the frame has an opening, the top of which is arched as indicated by numeral 15, to correspond with the 40 arching of the top of the plate; and a notch 16 provided in the front of the frame permits the passage of the boss 10.

45 Numeral 17 refers to an oil hole, and numeral 18 indicates a wick arranged beneath the crank pin, for the purpose of collecting the waste lubricant. To permit access to the interior of this portion of the frame I provide a screw plug 19.

In Figure 7, I have shown on an enlarged 50 scale, a slightly modified form of the invention. In this construction I employ two rows of entering pins, 20 and 21, the pins being arranged in staggered relation, and the pins of the upper row being slightly 55 longer than those of the lower row. It will be understood, of course, that any desired number of rows may be employed, and the pins may be mounted in the plates in any preferred manner. The particular means 60 shown in this figure for mounting the entering pins, consists in securing each row of pins between two plates; and then when two rows are to be employed, as in Figure 7, the plates carrying the longer set of pins are 65 placed on top of the plates carrying the

shorter set of pins, and the two sets secured together by means of screws 22. It is not my intention to be limited to any particular details of construction in connection with the use of two or more rows of pins, the aim 70 being merely to provide the most simple construction whereby additional rows may be applied or removed from the apparatus in accordance with the requirements of the particular fabric being treated. 75

In the use of the apparatus it is found that when all the pins of a single row are of the same length, the pins adjacent the sides enter the material farther than do the centrally arranged pins, and for that reason I have 80 found it desirable to gradually increase the length of the pins toward the center, as clearly shown in Figures 1 and 2.

Obviously it will be desirable to use pins 85 of various sizes, and arranged at various intervals, in accordance with the character of the fabric being treated, and it is therefore highly desirable that the plate or plates suited to the occasion may be quickly mounted in the apparatus. An inspection of Figure 90 1 will show that in order to remove a plate, it is only necessary to remove screw 11, thereby allowing the plate to be withdrawn, the boss passing through the notch 16.

As previously pointed out, the plate carrying the entering pins reciprocates rapidly, 95 and as it is drawn over the garment or other fabric the pins enter the fibre and loosen it up, so that it is restored to substantially its original condition; and this result is produced without abrasive or other destructive action on the fibre. It may also be mentioned here that this opening up of the fibre greatly facilitates the cleansing of a garment or other fabric, as it permits the detergent to freely enter the fabric. Better 105 results are produced if the material to be treated is moistened before being subjected to the action of the machine, but this is not essential. 110

By an inspection of Figure 1, it will be noted that the apparatus is not advanced over the material, but is drawn rearwardly, so that there is no tendency whatever to injure the material. 115

It will be understood that the pins enter the material at an angle to the plane thereof, and that this angle may vary from an extremely small one, almost 0, to a very large one. 120

While the apparatus is primarily designed for removing the shine from material and restoring the nap thereto, it is obvious that the action of the pins loosens up the fibre, and hence greatly aids in all cleansing operations. It is thus clear that the apparatus is adapted to use in connection with the cleansing of all fabrics, such as clothing, portières, rugs, carpets, etc. 125

It is also to be noted that as the apparatus 130

is carried by the hand it permits ready access to the usually inaccessible parts of a garment.

In cases where I make the apparatus of such size as to be too heavy to be carried by the hand for any great time, it will be found desirable to suspend the machine from any conventional counterbalancing apparatus, and this may be done without losing any of the advantageous results of the machine.

In treating fabrics of large dimensions it may be found desirable to hold the machine stationary and to move the fabric in the manner desired.

It is to be emphasized that the use of my apparatus does not result in any temporary or artificial removal of the shine from garments or other fabrics, but the effect produced is to loosen and lighten up all the fibre, so that in fact the fabric is restored to substantially its original condition.

In accordance with the patent statutes I have described what I now believe to be the best embodiment of my invention, but I do not wish to be understood thereby as limiting myself or the scope of my invention, as many changes and modifications may be made without departing from the spirit of the invention, and all such I aim to include in the scope of the appended claims.

What I claim as new, and desire to secure by Letters Patent is:

1. A hand operated machine of the character described, including a series of rigid entering pins, and means for longitudinally reciprocating said pins.

2. An apparatus of the character described, including a frame, a series of rigid entering pins mounted in the frame, and means for rapidly reciprocating said pins longitudinally.

3. An apparatus of the character described, including a frame, a plate mounted for reciprocation in said frame, a series of entering pins carried by said plate, and means for longitudinally reciprocating the plate.

4. An apparatus of the character described, including a frame, a plate mounted for reciprocation in said frame, a series of rigid entering pins carried by said plate, and means for longitudinally reciprocating the plate.

5. An apparatus of the character described, including a frame, a plate mounted for longitudinal reciprocation in said frame, a series of rigid entering pins carried by said

plate, a motor attached to said frame, and means operatively connecting the motor with the plate.

6. An apparatus of the character described, including a frame, a plate mounted for longitudinal reciprocation in said frame, a series of pins carried by said plate, a motor attached to said frame, a crank pin carried by the motor shaft, and a connecting rod connecting the crank pin and plate.

7. An apparatus of the character described, including a frame, a plate mounted for reciprocation in said frame, pins carried by said plate, means for longitudinally reciprocating said plate, and means whereby the plate may be removed from the frame.

8. An apparatus of the character described, including a frame, a plate mounted for reciprocation in said frame, pins carried by the plate, means for longitudinally reciprocating the plate, said means including a connecting rod and a pin detachably connecting the rod to the plate.

9. An apparatus of the character described, including a frame, a plate mounted for reciprocation in said frame, a series of pins carried by the plate, said plate being recessed on its lower side whereby friction is reduced, and means for longitudinally reciprocating the plate.

10. An apparatus of the character described, including a series of rigid entering pins, the length of the pins gradually increasing from the sides toward the center of the series, and means for longitudinally reciprocating said pins.

11. A hand operated machine of the character described, including a frame, a plate mounted for reciprocation in said frame, a series of rigid entering pins carried by said plate, the length of the pins gradually increasing from the sides toward the center of the series, and means for longitudinally reciprocating said plate.

12. An apparatus of the character described, including a frame, a plurality of plates mounted for longitudinal reciprocation in said frame, pins carried by the plates, the pins of one plate being of greater length than the pins of another of the plates.

13. An apparatus of the character described, including a frame, a plurality of plates mounted for longitudinal reciprocation in said frame, pins carried by the plates, the pins being arranged in staggered relation.

MURRAY T. DONOHO.
